UNITED STATES PATENT OFFICE.

EDWIN E. SLICK, OF PITTSBURGH, PENNSYLVANIA.

APPARATUS FOR FORGING METAL.

1,114,396.

Specification of Letters Patent.

Patented Oct. 20, 1914.

Application filed December 20, 1912. Serial No. 737,790.

To all whom it may concern:

Be it known that I, EDWIN E. SLICK, a citizen of the United States, residing at Pittsburgh, in the county of Allegheny and State of Pennsylvania, have invented certain new and useful Improvements in Apparatus for Forging Metal, of which the following is a specification.

My invention relates to the construction 10 of apparatus used in forging metal, and while not restricted to such use more particularly relates to apparatus used in rolling or roller-forging solids of revolution such as, for example, integrally formed car 15 wheels having hub, web and tread portions.

One object of this invention is to provide apparatus for forging metal, of improved construction, having opposed, relatively movable die faces whereby the metal being 20 rolled or forged is caused to assume the desired form, and having novel means by which the relative travel or movement of the opposing die faces toward and away from each other is regulated and controlled 25 and is adjusted or restricted to bring the opposing die faces to a stop at a predetermined distance apart at the completion of successive forging operations.

Another object of the invention is to provide 30 apparatus for forging metal having improved means whereby the opposing die faces are caused to move toward and away from each other and the amount of forward movement or movement of approach is adjusted and controlled.

A further object of my invention is to provide a novel construction and arrangement of the opposing rotary die supports and means whereby the opposing die supports 40 are secured together and held in place, and by which positioning the materials being rolled between the die faces is facilitated and the time required in such positioning operations is lessened.

A still further object of my invention is to provide a roller-forging machine having novel means whereby the strains set up in the operation of the apparatus are distributed and equalized, and further objects of 45 the invention will appear as the apparatus is more fully described and claimed hereinafter.

Referring to the drawings, forming part of this specification, Figure 1 is a plan showing 50 apparatus for forging constructed and arranged in accordance with my invention.

Fig. 2 is a side elevation of the same, partly in section, the section being taken on the line II—II of Fig. 1. Fig. 3 is a sectional end elevation, the right hand half of the section 60 being taken on the line III—III of Fig. 1, and the left hand half on the line IV—IV of Fig. 1. Fig. 4 is a sectional side elevation showing a modified form of forging apparatus constructed in accordance with my invention. Fig. 5 is a front elevation of the apparatus shown in Fig. 4.

In Figs. 1, 2 and 3 of the accompanying drawings, the numerals 2 and 3 designate forging dies removably secured to the 70 flanges 4 and 5 on the adjoining ends of horizontally extending rotary shafts 6 and 7, which are mounted in roller thrust-bearings 8 and 9 located at opposite ends of the apparatus. Bearings of any approved construction may be employed in place of the 75 particular type shown.

The shafts 6 and 7 are arranged to extend lengthwise between the horizontal box girders 10 and 11, the axial center of the shaft 80 6 in a horizontal plane extending at a slight angle to that of the shaft 7. One end of each of the box girders 10 and 11 is secured to the base-plate or bed-plate 12 which is also constructed to form a support between 85 the girders 10 and 11 for the thrust bearing 8 in which the shaft 6 is rotatably mounted. The opposite end of each of the girders 10 and 11 is connected to the flange 13 conveniently formed on one end of the single-acting 90 hydraulic cylinder 14 and the cylinder 14 is mounted upon one end of the base-plate 15 provided for that purpose. The base plate 15 is also provided with side portions engaging with and supporting the ends 95 of the girders 10 and 11 connected to the flange 13 of the cylinder 14.

Tie-bolts 16 and 17, having nuts 18 on the screw threaded ends thereof, extend horizontally through suitable openings in the 100 hollow girders 10 and 11 to secure the base plate 12, forming the support for the bearing 8, to the cylinder 14, located at the opposite end of the girders, and to secure the girders 10 and 11, the base plate 12 and the 105 cylinder 14 in assembled relation.

The axes of the shafts 6 and 7, the tie rods 16 and 17, and the girders 10 and 11, are all in the same horizontal plane, as will be seen by reference to Figs. 2 and 3, this construction equalizing the strains put upon the 110 apparatus during the rolling operations and

avoiding any obstruction or hindrance to the insertion and centering of the metal blanks between the dies in position to be rolled from a position immediately above the apparatus.

Through-bolts 19 extend vertically through registering openings provided for that purpose in the base plate 12, one end of the girders 10 and 11 and the removable bearing cap 20 forming part of the support for the thrust bearing 8, to rigidly secure the bearing in position and similar through-bolts 21 are employed to secure the girders 10 and 11 to the base plate 12 and to the base plate 15. The base plates 12 and 15 are secured upon a suitable foundation 22 by means of foundation bolts, in the usual manner.

The outer end of the shaft 6, or shaft to which the die 2 having an angular face is secured, is provided with a wobbler connection 23 which is connected by means of a coupling box 24 to one end of a spindle 25 and the spindle 25 is connected by its opposite end to the driving shaft of a steam engine motor, or other prime mover (not shown).

By reference to Fig. 1 it will be seen that the lines of contact of the opposite die faces with the blank A in a horizontal plane, through the longitudinal center of the die shafts and dies, are parallel although the axis of rotation of the shaft 6 is not parallel to that of the shaft 7.

The die shaft 7 which rotates in its bearing 9 will be driven or caused to rotate by frictional engagement with the metal being operated on between the die faces 2 and 3 during the rolling operations but, in order to overcome the inertia of the rotary shaft 7 and parts supported thereon at the beginning of the successive rolling operations, a spur gear 26 on the shaft 7 is connected by slow-down gears 27 and 28 to an electric shaft driving motor 29 which is conveniently mounted on top of the bearing 9. The motor 29, obviously, may, when desired, be operated to prevent the shaft 7 from stopping between successive rolling operations so that the shaft 7 will constantly rotate or the motor may in some cases be omitted.

The bearing 9 carrying the shaft 7 is arranged to reciprocate horizontally in a direction parallel to the axis of the shaft 7, the opposite sides of the bearing 9 being provided with guides 9a which engage with the slides 30, 30, 31, 31, located on the sides of the girders 10 and 11 and the rear end of the bearing 9 is connected to the flange 32 on one end of the plunger 33 which is operatively mounted in the single-acting hydraulic cylinder 14 forming the power means for causing a relative approach of the forging die faces during the rolling operations.

Single-acting pullback cylinders 34, 34,

which are formed within the body of the casting forming the cylinder 14 on opposite sides of the axis of the cylinder 14, have plungers 35 mounted therein which are connected by one end to the ends of a crosshead 36, the plungers 35 and crosshead providing means for moving the plunger 33 backwardly and the crosshead forming a stop operatively engaging with the rear end of the cylinder 14, for a purpose described later.

The plunger 33 is hollow and is provided with an axial opening through which the rod or shaft 37 extends, a forcing fit being made between the rod and plunger, and the rod or shaft, adjacent to one end, is provided with a flange 38 which is positioned in the counterbored portion 39 of the hollow plunger 33. The other end of the shaft 37 extends through the stuffing box 40 and gland in the rear end of the cylinder 14, and is adjustably connected by means of the screw threaded nut 41 and lock nut 42 to the crosshead 36 to which the plungers 35 of the two pullback cylinders 34 are connected. In this way the outward stroke of the piston 33 in the cylinder 14 is varied and the distance between the faces of the dies 2 and 3, when at the end of their approaching movement, is adjusted as is desired, and the dies are caused to come to a stop at a predetermined distance apart in the successive rolling operations by engagement of the crosshead 36 with the end of the cylinder 14.

A tapering pin 43 is provided which is removably secured in the axially central recess or hole in the die 3 to center the blanks between the die faces and the rear end of the rolling pin 43 is engaged by one end of a pushing rod 44 which has a flange 45 at an intermediate point in its length.

The rod 44 extends lengthwise through the axial opening in the shaft 7 and engaging with one side of the flange 45 on the rod is a hollow housing 46 having helical spring 47 positioned therein. The inner end of the rod 44 is secured by a pin or otherwise fastened to one end of the plunger 48 operatively mounted in the cylinder which is formed by the opening or recess 49 in one end of the rod or shaft 37.

The outer end of the plunger 48 engages with the spring 47 in the housing 46, and the housing 46 engages by one end with a shoulder formed on the interior of the hollow shaft 7 so that when the plunger 48 is advanced in the cylinder 49 the spring 47 is compressed, this same movement of the plunger 48 moving the rod 44 lengthwise so as to push the taper pin 43 from its seat in the die 3, as will be explained more fully hereinafter. The cylinder 49 is provided with a stuffing box 50 and gland 51 of the usual and well known construction and a fluid inlet opening is provided on the cylinder 130.

der to admit fluid pressure thereto for actuating the plunger 48.

The die 2 having an angular forming face and the die 3, which are mounted on the adjacent ends of the shafts 6 and 7, are constructed to form flanged wheels A, but by substituting other similarly formed dies, other solids of revolution are formed to the desired contour and size.

9 In the modified forging apparatus shown in Figs. 4 and 5 the base plate 52, which is secured upon a suitable foundation, is connected by means of four tie rods or bolts 53 to the lugs 56 on the single acting fluid pressure cylinder 57, and the cylinder 57 is provided with a downwardly extending plunger 58 having an extension or tail 59 thereon which projects through the rear or upper end of the cylinder 57, a stuffing 20 box 60 and gland 61 for the tail 59 of the usual construction being formed on the rear end of the cylinder 57.

The base plate 52 is provided with an anvil block 62 and the lower end of the 25 plunger 58 has an anvil block 63 removably secured thereto which co-acts with the anvil block 62 in the forging operations, and a stuffing box 64 and gland 65 are provided on the front or lower end of the cylinder 30 57 through which the plunger 58 projects, this stuffing box and gland also being of the ordinary construction.

Located on opposite sides of the recess in the cylinder 57 for the plunger 58 are two 35 parallel recesses forming single acting pull-back cylinders 66, 66, these cylinders having plungers 67 which project upwardly through the stuffing boxes 68 and glands 69 on the outer upper end of these cylinders. A cross-head 70 is secured on the rearwardly extending tail 59 of the plunger 58, this cross-head being adjustably held in position by means of the nut 71 on the screw threaded end of the tail 59, and a lock nut 72 is also 45 provided to hold the nut 71 in adjusted position. The ends of the crosshead 70 are connected to or engaged by the outer ends of the plungers 67 in the pull-back cylinders 66, these plungers serving to retract or lift 50 the plunger 58 in the operations of the forging apparatus.

The crosshead 70 has a stop portion 73 which engages with the end of the cylinder 57 and limits the downward or outward 55 movement of the plunger 58 in the same way as in the apparatus shown in Figs. 1, 2 and 3.

In the operation of my improved apparatus as shown in Figs. 1, 2 and 3 the motor 60 29 is started so as to cause the shaft 7 to rotate in its bearing 9 and the shaft 6 is positively driven, through the spindle 25 and coupling box 24 connected to the wobbler 23 on the end of the shaft 6, by starting 65 the engine or other driving motor. Fluid

pressure is then admitted to the pullback cylinders 34 to cause the die 3 to move backwardly and thereby bring the dies 2 and 3 into a relatively separated position, and a rolling pin 43 is then mounted in the axially central recess in the die 3.

Before starting to operate the apparatus in making wheels or other articles being formed, the crosshead 36 is positioned on the shaft 37 by manipulating the nut 41 and lock nut 42 on the screw threaded end of this shaft so that when the opposing faces of the dies 2 and 3 are moved toward each other by the plunger 33 to the fullest extent desired or necessary, the cross-head 36 will be in engagement with the rear end of the hydraulic cylinder 14, in this way forming a stop by which the possible relative approaching movement of the die faces is made uniform or constant in any number of successive forging operations. A heated blank is then inserted between the faces of the forging dies 2 and 3 and fluid pressure is admitted to the cylinder 14 so as to cause the plunger 33 to move outwardly within the cylinder 14 and move the die 3 toward the die 2, in this way bringing the metal between the die faces into working engagement with the angular face of the rotating die 2. The forward movement of the plunger 34 is then continued gradually while the dies and blank between the die faces are being rotated until the material being roller forged is formed to contour and size and when this occurs the crosshead 36 forming 100 the stop will be in engagement with the end of the cylinder 14 so that no further approaching movement of the die faces 2 and 3 is possible.

During the rolling or roller forging operation the metal is forged upon the taper pin 43 and will be found to tightly engage with this pin which makes it necessary or desirable in order to facilitate the rolling operations to remove the pin with the rolled wheel from the die 3 after each rolling operation. The pin 43 however may be tapered to such an extent that the metal being formed will not tightly grasp the pin in the rolling operations and in this way the same pin be used for an indefinite time. Fluid pressure is then admitted to the pull-back cylinders 34 which causes the plungers 35 to move outwardly therein and as the outer ends of these plungers are operatively connected to the crosshead 36 the shaft 37 is moved axially, which movement moves the plunger 33 inwardly within the hydraulic cylinder 14. This inward movement of the plunger 33 retracts the bearing 9 and shaft 7 mounted therein and the die 3 on the end of the shaft 7 so that the faces of the dies 2 and 3 are caused to separate. Fluid pressure is then admitted to the cylinder 49 formed in the end of the shaft 37 which 130

causes the plunger 48 to move outwardly therein, and this movement of the plunger 48, through the medium of the rod or shaft 44, forces the pin 43 from its seat in the die 3 and in this way removes or dislodges the wheel or other article from within the recesses of the die 3. The above described operations are then repeated with successive blanks in the continued use of the apparatus.

In the operation of the foregoing apparatus shown in Figs. 4 and 5, the anvil 63 is reciprocated vertically toward and away from the anvil 62 in the forging operations and the extent of the extreme downward or forging movement of the anvil 63 is regulated and controlled in successive strokes so as to always cause the anvil face to travel the same adjusted distance when moved by the plunger 58. In this way the minimum thickness to which an article is forged is made adjustable and is automatically controlled by adjusting the crosshead to hold the die faces the desired distance apart.

The advantages of my invention, which will be apparent to those skilled in the art, arise from the provision and novel construction of the stop by which the forging stroke or length of approaching movement of the die faces is regulated and controlled. The construction and location of the side girders enables the horizontal axis of the girders and the die supporting shafts to be in the same horizontal plane, which distributes the working strains and forces uniformly throughout the apparatus and enables the blanks to be easily and quickly inserted and removed from between the faces of the forming dies. By so constructing the forging apparatus, the difficulties in handling the metal in placing the metal blanks between the die faces are removed and lessened. By means of my improved pushing arrangement the pins upon which the metal is rolled are readily removed from the supporting die at the completion of each rolling operation.

Modifications in the construction and arrangement of the parts may be made within the scope of the appended claims without departing from my invention.

I claim:

1. Forging apparatus comprising in combination rotary shafts having their axes extending at an angle to each other, forming die faces on the ends of said shafts, means for positively driving at least one of said shafts and forming dies, means for causing a relative approach of said die faces, and means forming a stop to limit the approaching movement of said die faces.

2. Forging apparatus comprising in combination rotary shafts having their axes extending at an angle to each other and having opposed forming die faces on the ends

thereof, means for positively driving at least one of said shafts and forming dies, means for causing a relative approaching movement of the die faces, and means forming a stop to limit the approaching movement of said die faces, said stop being adjustable to vary the length of said approaching movement. 70

3. Forging apparatus comprising in combination rotary shafts having their axes extending at an oblique angle to each other, means for positively driving at least one of said shafts, means for causing a relative endwise approach of the shafts, and means forming a stop to limit said approaching 80 movement.

4. Forging apparatus comprising in combination rotary shafts having their axes extending at an oblique angle to each other, means for positively driving at least one of 85 said shafts, means for causing a relative endwise approach of said shafts, and means forming a stop to limit the approaching movement of the shafts, said stop being adjustable to vary the length of approaching 90 movement.

5. Forging apparatus comprising in combination rotary shafts having their axes extending at an oblique angle to each other, means for positively driving at least one of 95 said shafts, means for causing a relative endwise approach of the shafts in a path parallel to the axis of one of said shafts, and means forming a stop to limit the approaching movement of said shafts. 100

6. Forging apparatus comprising in combination rotary shafts having their axes extending at an oblique angle to each other, means for positively driving at least one of 105 said shafts, means for causing a relative endwise approach of the shafts in a path parallel to the axis of one of said shafts, and means forming a stop to limit the approaching movement of said shafts, said stop being adjustable to vary the length of 110 said movement of approach.

7. Forging apparatus comprising in combination rotary shafts having their axes extending at an oblique angle to each other, means for positively driving at least one of 115 said shafts, means for moving one shaft endwise toward the other, and means forming a stop to limit the length of endwise movement of said shaft.

8. Forging apparatus comprising in combination rotary shafts having their axes extending at an oblique angle to each other, means for positively driving at least one of said shafts, means for moving one shaft endwise toward the other, and means forming a stop to limit the length of endwise movement of said shaft, said stop being adjustable to vary the length of said movement of approach. 120

9. Apparatus for forging comprising in 13

5 combination rotary shafts axially disposed at an oblique angle in a horizontal plane and having forming die faces on adjacent ends thereof, means for positively driving at least one shaft, power means for causing a relative endwise movement of said shafts, horizontally disposed girders on opposite sides of said shafts to which the shaft bearings and shaft reciprocating means are secured, and tie bolts connecting the shaft bearings and shaft reciprocating means with said girders, the axes of said bolts and shafts being in 10 the same horizontal plane.

10 15 20 25 30 35 40 45 50 55 60 65 70 75 80 85 90 95 100

ders having plungers to move said shaft in the opposite direction, and a crosshead connecting the plungers for the pullback cylinders and single-acting cylinder, said crosshead being adjustable to form a stop whereby the stroke of said reciprocatory shaft is varied.

14. Forging apparatus comprising in combination opposed anvil faces, a fluid pressure cylinder having a reciprocating plunger, on which one of said anvil faces is mounted, for causing a relative approach of the anvil faces, and an adjustable stop by which the stroke of said reciprocating plunger is limited.

10. Apparatus for forging comprising in combination rotary shafts axially disposed at an oblique angle in a horizontal plane and having forming die faces removably secured on adjacent ends thereof, bearings for said shafts, means for positively driving at least one of said shafts, means for causing a relative movement of said die faces toward and away from each other, tie bolts connecting the shaft bearings and die reciprocating means, the axes of said dies and bolts being in the same horizontal plane.

15 which the stroke of said reciprocating plunger is varied to control the forging distance 80 between the anvil faces.

20 15. Forging apparatus comprising in combination opposed anvil faces, a fluid pressure cylinder having a reciprocating plunger on which one of said anvil faces is 85 mounted for causing a relative approach of the anvil faces, and an adjustable stop on said plunger by which the stroke of said reciprocating plunger and the anvil face thereon is varied and the forging distance 90 between the anvil faces is regulated and

11. Apparatus for forging comprising in combination rotary shafts axially disposed at an oblique angle in a horizontal plane and having forming die faces on adjacent ends thereof, means for independently rotating said shafts, power means for causing a relative endwise movement of said die faces, girders horizontally disposed on opposite sides of said shafts to which the shaft bearings and means for endwise movement are secured, and tie bolts connecting the shaft bearings and the shaft reciprocating means with said girders, the axis of said bolts and shafts being in the same horizontal plane.

12. Apparatus for forging comprising in combination rotary shafts axially disposed at an oblique angle in a horizontal plane and having forming die faces on adjacent ends thereof, bearings for said shafts, means for driving at least one shaft, a single-acting hydraulic cylinder having a plunger arranged to move one shaft endwise toward the opposite shaft, hydraulic pullback cylinders having plungers to move said shaft in the opposite direction, and a cross-head connecting the plungers for the pullback cylinders and single-acting cylinder, said crosshead forming a stop to limit the length of endwise movement of the reciprocating shaft.

13. Apparatus for forging comprising in combination rotary shafts axially disposed at an oblique angle in a horizontal plane and having forming die faces on adjacent ends thereof, bearings for said shafts, means for driving at least one shaft, a single-acting hydraulic cylinder having a plunger arranged to move one shaft endwise toward the opposite shaft, hydraulic pullback cylinder.

ders having plungers to move said shaft in the opposite direction, and a crosshead connecting the plungers for the pullback cylinders and single-acting cylinder, said cross-head being adjustable to form a stop whereby the stroke of said reciprocatory shaft is varied. 70

14. Forging apparatus comprising in combination opposed anvil faces, a fluid pressure cylinder having a reciprocating plunger, on which one of said anvil faces is mounted, for causing a relative approach of the anvil faces, and an adjustable stop by which the stroke of said reciprocating plunger is varied to control the forging distance between the anvil faces. 75 80

15. Forging apparatus comprising in combination opposed anvil faces, a fluid pressure cylinder having a reciprocating plunger on which one of said anvil faces is mounted for causing a relative approach of the anvil faces, and an adjustable stop on said plunger by which the stroke of said reciprocating plunger and the anvil face thereon is varied and the forging distance between the anvil faces is regulated and controlled. 85 90

16. Forging apparatus comprising in combination opposed anvil faces, a fluid pressure cylinder having a reciprocating plunger on which one of said anvil faces is mounted, for causing a relative approach of the anvil faces, fluid pressure pullback cylinders having plungers for retracting said reciprocating plunger, and a cross-head connecting said plungers, said cross-head forming a stop to control the forging stroke of said reciprocating plunger. 95 100

17. Forging apparatus comprising in combination opposed anvil faces, a fluid pressure cylinder having a reciprocating plunger, on which one of said anvil faces is secured, for causing a relative approach of the anvil faces, fluid pressure pullback cylinders having plungers for retracting said reciprocating plunger and the anvil face thereon, a crosshead connecting said plungers, said crosshead forming an adjustable stop to control the forging stroke of said reciprocating plunger, and adjusting means whereby the crosshead is held in adjusted position on the reciprocating plunger. 110 115

18. Forging apparatus comprising in combination opposed anvil faces, a fluid pressure cylinder having a reciprocating plunger on which one of said anvil faces is mounted for causing a relative approach of the anvil faces, a rearward extension projecting through said cylinder, and an adjustable stop on said extension whereby the stroke of said plunger is varied to control the forging distance between the anvil faces. 120 125

19. Forging apparatus comprising in com- 130

bination opposed anvil faces, a fluid pressure cylinder, having a reciprocating plunger on which one of said anvil faces is mounted, for causing a relative approach of the anvil faces, a rearward extension projecting through said cylinder, fluid pressure pull-back cylinders having plungers for retracting said reciprocating plunger and the anvil face thereon, a crosshead connecting the pullback cylinder plungers with the rearward extension on said reciprocating plunger, and a nut by which said crosshead is

adjustably secured on the reciprocating plunger extension, said crosshead forming a stop whereby the forging stroke of said reciprocating plunger and the anvil face thereon is varied and controlled.

In testimony whereof, I have heretunto set my hand.

EDWIN E. SLICK.
